Francis J. Richards,

UNITED STATES PATENT OFFICE.

WILLIAM F. GEHRIG, OF NEWARK, NEW JERSEY, ASSIGNOR TO ESSEX SPECIALTY CO.,
A CORPORATION OF NEW JERSEY.

TOY PISTOL.

1,321,817.

Specification of Letters Patent. Patented Nov. 18, 1919.

Application filed July 19, 1919. Serial No. 311,988.

To all whom it may concern:

Be it known that I, WILLIAM F. GEHRIG, a citizen of the United States, residing at Newark, in the county of Essex and State 5 of New Jersey, have invented certain new and useful Improvements in Toy Pistols; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 The present invention has reference, generally, to improvements in toy pistols; and the invention relates, more particularly, to a novel construction of repeating cap pistol.

The invention has for its principal object 20 to provide a very simple, cheap and easily constructed and assembled repeating cap pistol, in the structure of which the parts have been reduced to a minimum number, and in which said parts are designed to be made of 25 stamped sheet metal.

A further object of the present invention is to provide a novel cap feeding mechanism which forms an integral part of the trigger device and which automatically operates to 30 position a new cap for firing simultaneously with the operation of retracting the detonating hammer.

Other objects of the present invention, not at this time more particularly enumerated, 35 will be clearly understood from the following detailed description of the same.

With the various objects of my present invention in view, the same consists, primarily, in the novel construction of repeating cap pistol hereinafter set forth; and the invention consists, furthermore, in the various arrangements and combinations of the several devices and parts, as well as in the details of the construction of said 40 devices and parts, all of which will be more fully described in the following specification, and then finally embodied in the claims which are appended thereto.

The invention is clearly illustrated in the 50 accompanying drawings, in which:—

Figure 1 is a side elevation of the novel construction of repeating cap pistol, with one of the casing members removed to disclose the interior mechanism.

55 Fig. 2 is a top edge view of the pistol with

portions of the casing members broken away to disclose the interior mechanism.

Fig. 3 is a side elevation with portions of one of the side casings broken away to disclose the interior mechanism, the latter 60 being shown in operated positions assumed thereby upon the pulling of the trigger.

Similar characters of reference are employed in all of the above described views, to indicate corresponding parts. 65

Referring now to the said drawings, the reference character 1 indicates one casing shell and 2 the opposite casing shell. Said casing shells are shaped to simulate in general appearance and outline a magazine revolver or pistol. Said shells 1 and 2 are opposed with their hollow sides together, and then secured one to the other in any way convenient or desirable, so that together they provide a hollow casing within which is 70 mounted the operative mechanism of the pistol.

The operative mechanism of the pistol comprises a carrying plate 3, which is provided with lugs 4 adapted to be passed 75 through slots or openings 5 provided in the casing shell 1, and turned or clenched over to secure said carrying plate 3 in proper position within the hollow casing provided by the shells 1 and 2. To provide an additional 80 fastening means for said carrying plate 3, a lug 6 may be struck out of the shell 1 and thrust through a slot 7 provided in said carrying plate, and then clenched over the latter. Said carrying plate is provided at the 85 upper portion of its rearward vertical edge with an anvil-plate 8, the same being integrally formed with said carrying plate and turned outwardly from the body of the latter to extend at right angles thereto. In 90 like manner said carrying plate is provided at the lower portion of its rearward vertical edge with a guide-plate 9, the same being integrally formed with said carrying plate and turned outwardly from the body of the 95 latter to extend at right angles thereto, and in vertical alinement with said anvil plate 8. Also bent outwardly from said carrying plate at its rearward vertical edge intermediate said anvil-plate 8 and said guide-plate 100 9, is a guard finger 10.

Fixed on said carrying plate 3 so as to project outwardly therefrom is a hammer fulcrum post 11. The hammer member comprises a sheet-metal plate 12 having side 110

flanges 13 at each side bent forwardly at right angles to said plate 12. The upper ends of said side flanges 13 terminate in free ears 14 the rearward edges 15 of which 5 are inclined upwardly and forwardly. Said plate 12 possesses an upwardly extending tongue providing a hammer point 16 which is bent forwardly to lie against the inclined edges 15 of said ears 14. As thus constructed 10 said the hammer point 16 is disposed at such an angle relative to the main plate 12, that when the hammer point 16 contacts with said anvil-plate 8, upon the rearward swinging movement of the hammer member, the 15 same will register against said anvil-plate in proper parallel relation thereto. Said side flanges 13 are provided with perforations in their lower ends adapted to receive said fulcrum post 11 to pivotally mount said hammer member thereon. One of said side flanges 13 has an integral forward extension 17 from which extends an upwardly projecting arm 18 having at its inner marginal edge an inwardly off-set lip 19. A spring 20 member 20 is coiled about said fulcrum post 11 between said side flanges 13 one extremity or arm 21 of which bears against a holding lug 22 bent outwardly from said carrying plate 3, and the other extremity or arm 23 30 of which bears against the plate 12, all in such manner that when the hammer member is swung outwardly to cocking position, said spring 20 is placed under tension which, when the hammer member is released will 35 impel the same forcefully against the anvil-plate 8.

Fixed on said carrying plate 3, below and slightly forward of said hammer fulcrum post 11 is a trigger fulcrum post 24. The 40 trigger member comprises a body-portion 25 doubled upon itself laterally into a U-shape, said body-portion 25 terminating at its lower end in a downwardly projecting trigger portion or finger piece 26, which 45 projects exteriorly of the casing comprised of the shells 1 and 2 through an opening 27 formed in the same. Said U-shaped body-portion 25 is provided with a rearwardly indented slot 28 which straddles said 50 fulcrum post 24, thereby pivoting said body-portion and trigger portion on said fulcrum post. The inner termination or end of said slot 28 is normally engaged against the fulcrum post 24, thereby fixing the normal initial 55 position of the trigger member, but at the same time permitting, by reason of the slotted mounting, a slight rearward bodily movement of the body-portion 25 in addition to the pivotal swinging motion imparted thereto upon pulling the trigger portion or finger piece 26. A spring member 29 is coiled around said fulcrum post 24 between the sides of said U-shaped body-portion 25, one extremity or arm 30 of which bears 60 against a holding lug 31 bent outwardly

from the lower edge of said carrying plate 3, and the other extremity or arm 32 of which bears against the trigger portion or finger piece 26, all in such manner that when the trigger member is pulled, said spring 29 is 70 placed under tension which serves when the trigger member is released to return the same to the normal initial position.

Integrally connected with one side of said U-shaped body-portion 25 is a rearwardly 75 extending arm 33, connected with the free end of which is a horizontal push-piece 34, the free end 35 of which co-operates with said guide-plate 9 of said carrying-plate 3 in the operation of feeding forward the ammunition strip, but which is normally withdrawn or spaced away from the said guide plate 9.

Integrally connected with said body-portion 25, so as to project upwardly therefrom 85 is a hammer tripping arm or lever 36, the same being provided at its free end with a laterally projecting nosing 37 having a chamfered rear edge 38, said nosing being adapted to co-operate with the off-set lip 90 19 of the arm 18 of said hammer member to operate the latter.

The ammunition strip 39 provided at regularly spaced intervals throughout its length with fulminate portions 40 is coiled 95 in the hollow handle portion of the casing provided by the shells 1 and 2, so as to be located below and in the rear of said carrying plate 3. The free end of said ammunition strip is led upwardly over the forward face of said guide-plate 9, to pass in the rear of said guard finger 10, and thence over the forward face of said anvil-plate 8 to position a fulminate portion 40 thereof in the path of, and ready to receive the impact of, said hammer point 16.

The operation of the parts is as follows:—

The ammunition strip 39 being threaded into operative relation to the guide-plate 9, the trigger portion 26 is pulled rearwardly by pressing the finger against the same. The first movement of the trigger portion 26 moves rearwardly, and bodily, the body portion 25, so as to carry the push-piece 34 into engagement with the ammunition strip 39 where the same rests against the guide-plate 9. Continued movement of the body-portion under the pull of the trigger portion oscillates the same on the fulcrum post 24, thereby causing the push-piece 34 to ride upward against the guide-plate 9, thereby pushing or feeding upward the ammunition strip 39, the slot 28 permitting a continued rearward movement of the body-portion 25 in company with its swinging movement whereby the push-piece 34 is maintained in operative contact with the ammunition strip 39 during the whole period of operative movement of the trigger member. Simultaneously with the upward feed- 130

ing movement thus imparted to the ammunition strip 39 occurs the cocking movement of the hammer member, whereby the same is withdrawn from the anvil-plate, leaving 5 unobstructed access thereto of the upwardly fed ammunition strip. The cocking of the hammer member is produced by the forward swinging movement of the tripping arm 36 induced by the swing of the trigger member. 10 Said forward swinging movement of the tripping arm 36 carries its nosing 37 into engagement with the off-set lip 19 of the arm 18 of the hammer member, thereby causing a forward swinging of the hammer 15 member on the fulcrum post 11 against the tension of the spring 20. This movement continues until the nosing 37 passes away from the lip 19 due to the yielding of the hammer member to the pressure of the nosing 20 whereby the latter rides upwardly upon the lip 19 until it clears the end of the latter, whereupon the hammer member is released to receive the opposite swinging impulse imparted thereto by the tension of the 25 spring 20, so that the same is snapped back forcefully against the fulminate portion 40 registered against the anvil-plate 8 in the path of the hammer point 16, resulting in a detonation of said fulminate portion 40. 30 The pressure of the finger is now released from the trigger portion 26, so that the spring 29 may exercise its tension to return the trigger-member and associated parts to normal initial position. In so returning to 35 normal position the trigger member swings rearwardly the tripping arm 36, during which movement the chamfered rear edge 38 of the nosing 37 rides over the off-set lip 19 of the hammer member, a sufficient lateral 40 play being provided for in the mounting of the trigger member to permit such operation. The parts are now all returned to normal initial position, and the above described operations may be repeated indefinitely to cause repeated detonations of the 45 fulminate portions 40 of the ammunition strip 39, until the latter has been entirely used up.

It will be apparent from the above description that I have produced a very simple, yet efficient repeating cap pistol, in the construction of which there are but two main movable parts, consequently providing a structure of durability, as well as a structure 55 little likely to be accidentally disarranged or rendered inoperative. Furthermore, all the parts of the mechanism and mountings are designed to be made of sheet metal stampings, thus providing a structure which 60 can be produced very rapidly and cheaply, and in large quantities.

I am aware that some changes may be made in the general arrangements and combinations of the various devices and 65 parts as well as in the details of the con-

struction of the same without departing from the scope of my present invention as described in the foregoing specification, and as defined in the appended claims. Hence, I do not limit my invention to the exact arrangements and combinations of the various devices and parts as set forth in the foregoing specification, nor do I confine myself to the exact details of the construction of said parts as illustrated in the accompanying drawings.

I claim:

1. A repeating cap pistol comprising a pair of shell members secured together to provide a casing; a carrying plate secured within said casing; said carrying plate having formed in connection with its rear vertical edge a transverse anvil-plate, a transverse guide-plate and a transverse guard finger intermediate of and spaced in a parallel plane forward of said anvil-plate and said guide-plate; a fulcrum post; a spring thrown hammer member pivoted upon said carrying plate forward of said anvil-plate and having a hammer point adapted to contact with the latter; a spring returned trigger member; a fulcrum post upon which said trigger member is mounted for a combined rearward bodily movement and a pivotal movement; means on said trigger member coöperating with said guide-plate to feed a strip of ammunition upwardly against said anvil-plate; and means on said trigger member for tripping said hammer member.

2. A repeating cap pistol comprising a pair of shell members secured together to provide a casing; a carrying plate secured within said casing; said carrying plate having formed in connection with its rear vertical edge a transverse anvil-plate, a transverse guide-plate, and an intermediate guard finger spaced in a parallel plane forward of said anvil-plate and said guide plate; a fulcrum post extending from said carrying plate; a hammer member pivoted on said fulcrum post provided with a hammer point adapted to move into parallel contact with the face of said anvil-plate, spring means for effecting the operative detonating stroke of said hammer member; a forwardly and upwardly extending arm connected with said hammer member provided at its rear edge with an off-set lip; a second fulcrum post extending from said carrying plate; a spring returned trigger member mounted for both bodily rearward and pivoting movement on said second fulcrum post; means on said trigger member coöperating with said guide-plate to feed a strip of ammunition upwardly against said anvil-plate; and a tripping arm extending upwardly from said trigger member for coöperating with said off-set lip of said arm of said hammer member to cock and trip the latter.

3. A repeating cap pistol comprising a pair of shell members secured together to provide a casing; a carrying plate secured within said casing; said carrying plate having formed in connection with its rear vertical edge a transverse anvil-plate, a transverse guide-plate, and an intermediate guard finger spaced in a parallel plane forward of said anvil-plate and said guide plate; a fulcrum post extending from said carrying plate; a hammer member pivoted on said fulcrum post provided with a hammer point adapted to move into parallel contact with the face of said anvil-plate, spring means for effecting the operative detonating stroke of said hammer member; a forwardly and upwardly extending arm connected with said hammer member provided at its rear edge with an off-set lip; a second fulcrum post extending from said carrying plate; a spring returned trigger member mounted for both bodily rearward and pivoting movement on said second fulcrum post; a rearwardly extending arm connected with said trigger member; a horizontal push-piece connected with said latter arm adapted to be carried by the movements of said trigger member into upwardly sliding relation to said guide-plate to feed a strip of ammunition upwardly against the face of said anvil-plate; and a tripping arm extending upwardly from said trigger arm, said tripping arm having a nosing adapted to engage said off-set lip of said arm of said hammer member to cock and trip the latter, said nosing having a chamfered rear edge adapted to ride over said off-set lip when said tripping arm returns with said trigger member to normal initial position.
4. In a repeating cap pistol a transverse anvil-plate, a transverse guide-plate vertically alined below said anvil-plate, a transverse guard finger intermediate said anvil-plate and said guide-plate and spaced forwardly thereof, a pivoted hammer member, spring means for throwing said hammer member, a trigger member mounted for both bodily rearward and pivoting movement beneath said hammer member, spring means for returning said trigger member to normal initial position after actuation, a rearwardly extending arm connected with said trigger-member, a horizontal push-piece connected with the free end of said latter arm adapted to be carried by the operative movements of said trigger member into upwardly sliding relation to said guide-plate to feed a strip of ammunition upwardly against the face of said anvil-plate, and a tripping arm extending upwardly from said trigger member to engage, cock and trip said hammer member.
5. In a repeating cap pistol a transverse anvil-plate, a transverse guide-plate vertically alined below said anvil-plate, a transverse guard finger intermediate said anvil-plate and said guide-plate and spaced forwardly thereof, a pivoted hammer-member, spring means for throwing said hammer member, a trigger member mounted for both bodily rearward and pivoting movement beneath said hammer member, means on said trigger member for cocking and tripping said hammer member, and means on said trigger member coöperating with said guide-plate to feed a strip of ammunition upwardly against said anvil-plate.
6. In a repeating cap pistol means for holding and guiding a strip of ammunition including an anvil member, a pivoted hammer member adapted to strike said anvil member, spring means for throwing said hammer member, a trigger member mounted for both rearward bodily and pivoting movements, said trigger member having a rearwardly extending arm carrying a push-piece adapted to cooperate with said holding and guiding means to feed said strip of ammunition upwardly against said anvil member, a tripping arm connected with said trigger member for cocking and tripping said hammer member, and spring means for returning said trigger member and associated parts to normal initial position.
7. In a repeating cap pistol means for holding and guiding a strip of ammunition including an anvil-member, a pivoted hammer member formed of sheet metal comprising a plate having side flanges extending from its longitudinal edges, upwardly extending ears having upwardly and forwardly inclined rear edges at the upper ends of said side flanges, said plate having an upwardly extending tongue bent back against said inclined edges of said ears to provide a hammer point adapted to rest in parallel contact with said anvil member, spring means for throwing said hammer member, one of said side flanges of said hammer member having an upwardly inclined forwardly off-set arm the rear edge of which is provided with a laterally off-set lip, a trigger member mounted for both rearward bodily and pivoting movements, a tripping arm extending upwardly from said trigger member having a laterally extending nosing at its free end to engage said off-set lip to cock and trip said hammer member, means on said trigger member coöperating with said holding and guiding means to feed upward said strip of ammunition against said anvil member, and spring means for returning said trigger member and associated parts to normal initial position.
8. In a repeating cap-pistol means for holding and guiding a strip of ammunition including an anvil-member, a pivoted hammer-member formed of sheet metal comprising a plate having side flanges extending from its longitudinal edges, upwardly ex-

tending ears having upwardly and forwardly inclined rear edges at the upper ends of said side flanges, said plate having an upwardly extending tongue bent back 5 against said inclined edges of said ears to provide a hammer point adapted to rest in parallel contact with said anvil member, spring means for throwing said hammer member, one of said side flanges of said 10 hammer member having an upwardly inclined forwardly off-set arm the rear edge of which is provided with a laterally off-set lip, a trigger member mounted for both rearward bodily and pivoting movements, a 15 tripping arm extending upwardly from said trigger member having a laterally extending nosing at its free end to engage said off-set lip to cock and trip said hammer member, means on said trigger member coöperating with said holding and guiding means to feed 20 upward said strip of ammunition against said anvil member, comprising a rearwardly extending integral arm carrying at its free end a horizontal push-piece, and spring means for returning said trigger member 25 and associated parts to normal initial position.

In testimony that I claim the invention set forth above I have hereunto set my hand this 9th day of July 1919.

WILLIAM F. GEHRIG.
